[57] **CLAIM**

The ornamental design for a multi-function telephone base for telephone handset, as shown and described.

DESCRIPTION

FIG. 1 is a top front, right side perspective view of a multi-function telephone base for telephone handset, showing my new design.

FIG. 2 is a top, front, right side perspective view thereof but with the handset removed from the base.

FIG. 3 is a top perspective view thereof.

FIG. 4 is a top perspective view of said multi-function telephone base for telephone handset in an open position.

FIG. 5 is a front perspective view thereof.

FIG. 6 is a bottom perspective view thereof.

FIG. 7 is a top right side perspective view thereof.

FIG. 8 is a top left side perspective view thereof; and, FIG. 9 is a rear perspective view thereof.

The handset has been omitted from FIGS. 3-5 and 7-9 for convenience of illustration.
